MINING APPARATUS

Charles F. Osgood, Claremont, N. H., assignor to
 Sullivan Machinery Company, a corporation of
 Massachusetts

Application December 13, 1941, Serial No. 422,800

3 Claims. (Cl. 262—28)

This invention relates to mining apparatus, and more particularly to improvements in the propelling mechanism of an apparatus for mining coal.

In coal mining apparatus of the wheel-mounted, track guided type, propulsion of the apparatus along the mine trackway is usually effected by the drive of the traction wheels of the apparatus. The traction wheels are driven at a relatively high speed during tramping of the apparatus about the mine and at a relatively low speed during the cutting operation, i. e. during the making of rectilinear sumping and withdrawal cuts in the coal. Under certain conditions, particularly when the machine is operating on a gradient, the traction wheels oftentimes lose their tractive effort by slippage; and at such times it is necessary to provide some form of auxiliary propelling means which may supplement the traction wheels in the propelling of the apparatus. Usually such auxiliary propelling means assumes the form of a haulage drum embodied in the apparatus and having wound thereon a haulage cable which is connectible extraneous to the apparatus to an appropriately located anchor jack. Furthermore, such auxiliary haulage means are usually driven at predetermined speeds approximating the propelling speeds of the traction wheels and are usually employed only during the rectilinear sumping and withdrawal cutting operations of the apparatus. Auxiliary propelling means of the haulage drum type have certain disadvantages since they lack flexibility and are time-consuming in operation, since it is necessary to extend the cable for attachment to the anchor jack and to rearrange the cable and anchor jack when reverse feed is desired.

An object of the present invention is to provide an improved auxiliary propulsion means for a coal mining apparatus of the wheel mounted, track guided type, which overcomes the disadvantages of previous known devices. Another object is to provide an improved supplemental propulsion means which is embodied in the apparatus and operable through a wide range of feeding speeds appropriate for cutting, and which may be quickly set into operation. Another object is to provide a novel auxiliary propulsion means for a coal mining apparatus of the wheel mounted, track guided type whereby the low speed track wheel propulsion means of the apparatus may be either supplemented or supplanted. A further object is to provide an improved hydraulically operated, cylinder and piston type propelling mechanism for a track mounted coal mining apparatus wherein the propelling mechanism is embodied in the ap-

paratus and is attachable to the rails of the mine trackway. Yet another object is to provide an improved auxiliary propelling means for a track mounted coal mining apparatus, which may be quickly placed into operation and may serve either to supplement or supplant the low speed truck wheel drive. A still further object is to provide a hydraulic jack mechanism pivotally connected to the apparatus and operated by a power source within the apparatus, for effecting propulsion of the apparatus during the cutting operation. A still further object is to provide an improved hydraulic jack mechanism embodied in the coal mining apparatus and attachable to the rails of the mine trackway upon which the apparatus is supported and guided. Another object is to provide a novel feed jack device connectible to the mining apparatus and an extraneous abutment for effecting propulsion of the apparatus along a mine trackway during the opposite rectilinear sumping and withdrawal cutting operations, and deriving its power from the mining apparatus. How these and other objects are accomplished and the advantageous features of the invention, will be best understood from the following detailed description wherein a preferred and illustrative embodiment is set forth, reference for the purpose being had to the accompanying drawings, in which:

Fig. 1 is a side elevational view of a coal mining apparatus in which an illustrative form of the invention is embodied.

Fig. 2 is an enlarged fragmentary view in side elevation of the rearward portion of the apparatus shown in Fig. 1, illustrating the improved auxiliary propelling means.

Fig. 3 is a sectional view, with parts in plan, showing the truck wheel driving mechanism.

Fig. 4 is a longitudinally extending vertical sectional view taken substantially on line 4—4 of Fig. 3.

Fig. 5 is an enlarged horizontal sectional view taken substantially on line 5—5 of Fig. 1.

Fig. 6 is an enlarged cross sectional view taken substantially on line 6—6 of Fig. 1.

Fig. 7 is a diagrammatic view illustrating the hydraulic system.

Fig. 8 is a diagrammatic side elevational view showing the improved coal mining apparatus making a horizontal cut in a mine entry.

Fig. 9 is a diagrammatic plan view showing the improved mining apparatus in a mine entry with the kerf cutter in its different horizontal cutting positions.

In this illustrative form of the invention the improved auxiliary propelling means is shown embodied in a coal mining apparatus of the wheel

mounted, track guided type. It will be evident, however, that the invention may be embodied in mining apparatus of various other types.

The coal mining apparatus disclosed herein may be of the same general character as that fully disclosed in the patent to Joseph F. Joy, Patent No. 2,229,087, patented January 21, 1941, and is of the well known universal type having kerf cutting mechanism adjustable through a relatively wide range, for cutting plane kerfs at various locations in the coal face. The mining apparatus comprises a truck frame 1 mounted on wheels 2 adapted to travel along a mine trackway 3 laid on the mine floor. The truck frame carries a forwardly located, horizontal turntable 4 on which is pivotally mounted at 5 a vertically swingable boom 6, the latter carrying a rotatable "turnover" cutter head 7. Pivotally mounted at 8 on the rotatable cutter head is a cutter support 9 carrying an elongated plane kerf cutter 10. Hydraulic cylinders 11 are employed for swinging the boom 6 in a vertical direction with respect to the turntable while hydraulic cylinders 12 afford means for rotating the cutter head 7. The cutter support 9 is swingable about its pivot by means of a hydraulic cylinder 13, and similar hydraulic cylinders 14 (shown in dotted lines in Fig. 1) are provided for rotating the turntable 4. Embodied in the apparatus are motors for driving the kerf cutter and the truck wheels and for actuating the pump which supplies liquid under pressure to the various hydraulically operated cylinders of the apparatus. The truck wheel driving motor is designated 15 (Fig. 4) and has its power shaft coupled to a longitudinal transmission shaft 16 suitably journaled in a gear housing 17. Fixed to the shaft 16 is a spur pinion 18 meshing with a spur gear 19, herein a high speed terminal gear, journaled on a longitudinal shaft 21. The gear 19 is connectible by a conventional friction clutch 20 to the shaft 21. Rotatable with and driven by the gear 19 is a spur pinion 22 meshing with a spur gear 23 fixed to a shaft 24. Also fixed to the shaft 24 is a spur pinion 25 meshing with a spur gear 26, herein a low speed terminal gear, likewise journaled on the shaft 24 and connectible by a conventional friction clutch 27 to the shaft. Keyed to the shaft 21 is a bevel gear 28 meshing with reverse bevels 29 and 30 journaled on a horizontal, transversely extending shaft 31, suitably journaled in the gear housing 17. The bevel gears 29, 30 (Fig. 3) are connectible by conventional frictional clutches 32 and 33 respectively, to the transverse shaft 31. Fixed to the opposite ends of the transverse shaft 31 are chain sprockets 34 connected by endless drive chains 35 to chain sprockets 36 fixed to the truck wheel axes. It is accordingly evident that under the control of the friction clutches 20, 27 the truck wheels may be driven at a relatively high tramping speed through the high speed gearing 18, 19 and at a relatively low speed appropriate for cutting through the low speed gearing 22, 23, 25, 26. By connecting one or the other of the reverse bevels 29, 30 to the shaft 31, the truck wheels may be driven in either of opposite directions at either speed. From the foregoing it will be evident that the kerf cutter may be adjusted through a wide range of cutting positions with respect to the coal face by adjusting the boom and cutter support and revolving the cutter head, and that the apparatus may be propelled by the truck wheels along a mine trackway all in the manner fully described in the patent above referred to.

Now referring to the improved auxiliary propelling means, it will be noted that arranged within longitudinal recesses 40, 40 at the opposite sides of the rearward portion of the truck frame are hydraulic jacks 41, 41. These jacks extend longitudinally of the apparatus and each comprise a hydraulic cylinder 42 universally pivotally connected at its forward end at 43 to a bracket 44 secured to the truck frame just rearwardly of the rear truck wheels, in the manner shown in Fig. 2. Reciprocable within each of the cylinders is a piston 45 having its piston rod 46 projecting rearwardly through the rear cylinder head 47. The piston rods at their rearward ends have universal pivotal connection at 48 with quick detachable clamps 49 attachable to the rails of the mine trackway. These clamps are grooved or recessed at 50 to receive the rail treads and have opposed gripping surfaces 51, 51 for gripping the opposite sides of the rail treads when the clamp is swung about an upright axis. Embodied in the apparatus is a conventional pump 52 arranged within a liquid reservoir 53, and this pump has its intake 54 submerged within the liquid in the reservoir. The pump discharge is connected through a conduit 55 to supply passages 56, 56 of a conventional valve box 57, and the passages 56 communicate with a valve receiving bore 58 which contains a slide valve 59. The valve box has a discharge passage 60 connected through a conduit 61 back to the reservoir. The valve receiving bore is connected through a conduit 62 with the rearward ends of the jack cylinders 42 and through a conduit 63 with the forward ends of the jack cylinders. Under the control of the slide valve, liquid under pressure may be supplied to either the forward ends or the rearward ends of the jack cylinders in an obvious manner. Suitable hooks 64 are attached to the truck frame by chains 65, and these hooks are connectible to the jack cylinders for holding the jacks in raised, inoperative position during tramping of the mining apparatus about the mine.

The coal mining apparatus may be propelled along the mine trackway during tramping at a relatively high speed under the propulsion of the truck wheels, and when the coal face is reached the truck wheel drive may be disconnected. The hydraulic jacks may then be swung downwardly with their clamps 49 in engagement with the track rails; and when liquid under pressure is supplied to the forward ends of the jack cylinders 42 under the control of the slide valve, the apparatus may be moved forwardly along the mine trackway at a relatively low cutting speed to sump the kerf cutter of the kerf cutting mechanism into the coal, in the manner shown in Fig. 8. When it is desired to move the mining apparatus rearwardly along the mine trackway to effect the withdrawal movement of the kerf cutter, liquid under pressure may be supplied to the rearward ends of the jack cylinders, and at that time the rail clamps automatically reverse to effect opposite gripping of the track rails. When it is desired to insert a horizontal kerf in the coal seam, as, for instance, at the level of the mine floor, the turntable 4 of the mining apparatus may be rotated by the hydraulic cylinders 14 to swing the boom horizontally into the full line position shown in Fig. 9, with the tip end of the kerf cutter 10 disposed near the right hand rib at the coal face. Liquid under pressure may then be supplied to the forward ends of the jack cylinders 42 to effect propulsion of the apparatus forwardly bodily along the mine trackway to ef-

fect rectilinear sumping movement of the kerf cutter into the coal from the full line position indicated at A in Fig. 9 to the dotted line position indicated at B. Liquid may then be trapped in the cylinders to hold the same stationary, thereby to hold the apparatus against bodily movement along the trackway. The turntable 4 may then be rotated to swing the boom horizontally from left to right, to move the kerf cutter arcuately across the coal face from the position indicated at B in Fig. 9 to the dotted line position indicated at C, thereby to make a transverse cut beneath the coal. During this operation entrapment of liquid within the forward ends of the cylinders will prevent the apparatus being thrust back from the face while the kerf cutter exerts a rearward reaction on the apparatus, and fluid can be admitted to the opposite ends of the cylinders to prevent forward movement of the apparatus during completion of the swinging cut, if desired. Liquid under pressure may then be supplied to the rearward ends of the jack cylinders 42 to move the mining apparatus bodily rearwardly along the mine trackway to effect rectilinear withdrawal movement of the kerf cutter from the position indicated at C in Fig. 9 to the dotted line position indicated at D. During the sumping and withdrawal movements of the mining apparatus, the truck wheels roll freely along the trackway, and during such operation the low speed truck wheel drive may be disconnected. When the kerf cutting operation is completed, the hydraulic jacks may be detached from the track rails and then swung upwardly into an out-of-the-way position within the recesses 40, and held in such position by the hooks 64. When the mining apparatus is making its rectilinear sumping and withdrawal cuts, while supported and guided by a mine trackway which is slightly curved, the universal pivotal connections 43 and 43 of the jacks with the truck frame and the rail clamps permit feeding movement of the apparatus along the curved trackway without distortion. The universal pivotal mountings for the jacks and rear clamps also permit movement of the mining apparatus along a mine trackway which is uneven. The hydraulic jacks may supplement the truck wheels in the propulsion of the apparatus during the kerf cutting operation or may supplant the low speed drive of the truck wheels.

As a result of this invention it will be noted that an improved auxiliary propelling means is provided for a coal mining apparatus of the wheel mounted, track guided type for propelling the apparatus through a wide range of feeding speeds appropriate for cutting. It will further be evident that the improved auxiliary propelling means is flexible and smooth in operation and may be quickly set into operation simply by attaching the rail clamps to the rails of the mine trackway. It will further be evident that by the provision of the improved propelling means, the low speed truck wheel propulsion means of the apparatus may be either supplemented or supplanted. Further, by the provision of the hydraulic jacks attachable to the track rails the apparatus may be readily propelled up an inclined trackway during the kerf cutting operation. Other uses and advantages of the invention will be clearly apparent to those skilled in the art.

While there is in this application specifically described one form which the invention may assume in practice, it will be understood that this

form of the same is shown for purposes of illustration and that the invention may be modified and embodied in various other forms without departing from its spirit or the scope of the appended claims.

What I claim as new and desire to secure by Letters Patent is:

1. In a mining apparatus, the combination comprising a wheel mounted, portable base guided for movement along a mine trackway, means for propelling the apparatus along the trackway at a relatively high speed during tramping, kerf cutting mechanism mounted on said base and adapted to cut a plane kerf in a coal seam, and means for feeding the apparatus bodily back and forth along the trackway at a relatively low speed suitable for cutting to effect rectilinear sumping and withdrawal movements of said kerf cutting mechanism, said low speed feeding means being entirely distinct from said high speed propelling means and comprising a longitudinally extending, axially extensible, hydraulic jack having its feeding range equal to the desired kerf depth, said jack having at its forward end a universal pivotal connection with said base and attachable at its rear end to the mine trackway, and means on said base for supplying fluid under pressure to said jack at a controlled rate.

2. In a mining apparatus, the combination comprising a wheel mounted, portable base guided for movement along a mine trackway, means for propelling the apparatus along the trackway at a relatively high speed during tramping, kerf cutting mechanism mounted on said base and adapted to cut a plane kerf in a coal seam, and means for feeding the apparatus bodily back and forth along the trackway at a relatively low speed suitable for cutting to effect rectilinear sumping and withdrawal movements of said kerf cutting mechanism, said low speed feeding means being entirely distinct from said high speed propelling means and comprising a longitudinally extending, axially extensible, hydraulic jack having its feeding range equal to the desired kerf depth, said jack having at its forward end a universal pivotal connection with said base, a quick detachable connection having a universal pivotal connection with the rear end of said jack for attaching the latter to the mine trackway, and means on said base for supplying fluid under pressure to said jack at a controlled rate.

3. In a mining apparatus, the combination comprising a wheel mounted, portable base guided for movement along a mine trackway, means for propelling the apparatus along the trackway at a relatively high speed during tramping, kerf cutting mechanism mounted on said base and adapted to cut a plane kerf in a coal seam, and means for feeding the apparatus bodily back and forth along the trackway at a relatively low speed suitable for cutting to effect rectilinear sumping and withdrawal movements of said kerf cutting mechanism, said low speed feeding means being entirely distinct from said high speed propelling means and comprising a longitudinally extending, axially extensible, hydraulic jack having its feeding range equal to the desired kerf depth, said jack having at one end a universal pivotal connection with said base and attachable at its other end to the mine trackway, and means on said base for supplying fluid under pressure to said jack at a controlled rate.

CHARLES F. OSGOOD.
